UNITED STATES PATENT OFFICE.

VOLNEY A. SEARLES, OF JACKSON, MICHIGAN, ASSIGNOR TO STEWART-WARNER SPEEDOMETER CORPORATION, OF CHICAGO, ILLINOIS, A CORPORATION OF VIRGINIA.

FUEL-FEEDING DEVICE.

Application filed September 4, 1923. Serial No. 661,319.

This invention relates to certain improvements in liquid feeding devices for use particularly in supplying liquid fuel to internal combustion engines of automobiles and the like, in connection with which it is very often desirable to have the primary fuel tank carried on the vehicle at a level below the carburetor.

The main object of the invention is to provide a device of comparatively simple construction and capable of efficient automatic operation, with particular relation to the construction of the vacuum tank portions thereof, to which the liquid fuel is elevated as by suction produced by the engine and intermittently discharged therefrom, to be fed by gravity to a vaporizing device, as for instance, to the float chamber of a commercial carburetor.

A further object relates to the particular construction of the valves and their supporting and operating means by which the automatic operation of the device is effected. Other objects and advantages relate to the details of construction of the device, all as will more fully appear from the following description, taken in connection with the accompanying drawings, in which:

Figure 1 is a vertical sectional view through the vacuum tank apparatus.

Figure 2 is an elevation of the valve controlling the suction and atmospheric lines.

The apparatus, as shown, consists of a tank —1—, divided by a partition wall —2— into an upper chamber —3— and a lower chamber —4—. The liquid fuel is adapted to be drawn into the upper chamber by means of vacuum produced therein in any suitable manner, and is intermittently discharged therefrom into the lower chamber —4— from which the liquid fuel may be fed by gravity, as through outlet —5— to any suitable consuming device, as the carburetor of an ordinary combustion engine.

To accomplish this end, the upper chamber is provided with a liquid inlet pipe —6—, adapted to be in communication with any suitable source of supply, as the ordinary low level tank carried upon the automobile. There is further provided for the upper chamber an atmospheric port —7— and a vacuum line or connection —8— leading to any suitable source of vacuum or suction, as the manifold of the internal com-

bustion engine. The communication of the atmospheric port —7— and the vacuum line —8— with the chamber —3— is controlled by means of a single rotary valve —9— positioned in valve casing —10— and in the position shown in Figure 1, the atmospheric port —7— is in direct communication with the upper chamber —3— through passageway —11— which brings the port —7— into communication with conduit —12— leading through the valve casing —10— and opening into the chamber —3—. In the same position of the valve, the suction line —18— is in communication with cylinder —13— formed in connection with the partition wall —2— and having arranged within it a piston —14— adapted to be actuated by suction and gravity. The communication between cylinder —13— and the vacuum line —8— is through the passageway —15— in the rotary valve —9— and the tube —16— which connects the valve casing with the cylinder —13—. In this position of valve —9—, the upper chamber —3— is unconnected with the vacuum line —8—, and the upwardly opening valve —17— controlling the passageway —18— between the upper chamber —3— and the lower chamber —4—, is opened, by reason of the fact that piston —14— has been raised by the suction produced in cylinder —13— so as to elevate the valve —17— against the action of the spring —19—, this operation being effected through the piston rod —20— and link —21— pivoted at —22— upon bracket —23— which may be secured to the partition wall —2—.

The link —21— carries the valve —17— by means of supporting arm —24— which may be pivotally connected to line —21— and rigidly connected to the valve —17— in any suitable manner.

The spring preferably surrounds the arm —24— and is confined between the stop plate —25— and the transverse bar —26— formed in connection with valve seat —27— and extending across the opening between the chamber —3— and the chamber —4— and having a vertical opening for the passage of the arm —24—. As shown, in Figure 2, the rotary valve —9— has a disk —28— formed on the outer end of its stem, such disk carrying a pair of spaced projections —29— and —30— with which the float arm —31— is adapted to contact when it

approaches its upper and lower limits of movement respectively. This float stem —31— is pivotally mounted on the outer end of the valve stem —32— so as to freely move about the valve stem without movement of the valve until contact of said float stem —31— with either the projection —29— or the projection —30—, dependent whether the chamber —3— is filling or emptying, in accordance with the position of the valve.

It will be understood, therefore, that the valve remains in stationary condition during all intermediate movements of the float stem, and only at substantially the upper limit of movement of said stem is the valve —9— rotated by contact of the stem with the projection —29—, and only at practically the limit of its lower movement is the valve rotated to bring the chamber —3— into communication with the suction and shut-off communication with the atmosphere by contact of the float stem —31— with the projection —30—.

It will be seen that when the float assumes its downward position where the stem —31— contacts with projection —30—, as indicated in dotted lines, Figure 1, the valve is then rotated to a position where the transverse passageway —11— brings the atmospheric port —7— into communication with the cylinder —13— through the pipe —16— and at the same time brings the angular passageway —15— into communication with the suction line —8— and the passageway —33— leading to the chamber —3—, so that vacuum will be produced therein. At that time the valve —17— is closed by spring —19—, the piston —14— being free to drop by reason of the atmospheric pressure existing in the pipe —16— and cylinder —13—. The spring —19— should be of sufficient strength to overcome the force of the vacuum produced in the chamber —3—. The chamber —4— is maintained at all times at atmospheric pressure by means of vent pipe —34— which may, as shown, penetrate the partition —2— and the cover —35— of the upper chamber —3—.

The operation of the structure is such that the spring —19— is of sufficient strength to close the valve when the piston —14— is free to move, due to the presence of atmospheric pressure in the pipe —16— and that when the pipe —16— is brought into communication with the suction line —8—, the force of the vacuum is sufficient to elevate the piston —14— against the action of spring —19— and open valve —17— to permit the free discharge of the liquid fuel from the chamber —3— into the chamber —4—.

Although I have shown and described a specific construction and method of operation as illustrative of a perhaps preferred embodiment of my invention, I do not desire to limit myself to the details of con-

struction or operation of the device, as various changes, modifications and substitutions can be made without departing from the invention as set forth in the appended claims.

I claim:

1. In combination with a pumping chamber adapted to be filled with liquid, a receiving chamber for liquid communicating with the pumping chamber, a valve controlling said communication arranged to open inwardly with respect to said pumping chamber, whereby the head of liquid in the chamber tends to hold the valve closed, and a suction operated motor for opening said valve in opposition to the head of liquid.

2. In combination with a pumping chamber and means for applying suction thereto for filling the chamber with liquid, a receiving chamber for the liquid communicating with the pumping chamber, a valve controlling said communication arranged to open inwardly with respect to the pumping chamber, a spring associated with said valve for yieldingly holding the valve closed in opposition to suction in the pumping chamber, and a suction operated motor for opening the valve in opposition to said spring.

3. In combination, a pumping chamber adapted to be filled with liquid by suction, an outlet for such liquid, a valve controlling the outlet arranged to open inwardly with respect to the chamber, a spring yieldingly holding the valve seated, a suction operated motor, and power multiplying means by which said motor is connected to the valve for opening it in opposition to the spring.

4. In a device of the class described, a chamber having an atmospheric connection and a suction connection, a rotary valve controlling both of said connections, a float in said chamber and means actuated by the float at substantially the limits of upper and lower movement for rotating said valve to the desired respective positions, a lower chamber, means of communication between said chambers, a valve controlling said communication, and suction actuated means for moving said valve to open position.

5. In a device of the class described, a chamber having an atmospheric connection and a suction connection, a rotary valve controlling both of said connections, a float in said chamber and means actuated by the float at substantially the limits of upper and lower movement for rotating said valve to the desired respective positions, a lower chamber, means of communication between said chambers, a valve controlling said communication, suction-actuated means for moving said valve to open position, and spring means for closing said valve.

6. In a device of the class described, an upper chamber having an atmospheric connection and a suction connection; a lower

chamber with means of communication between said chambers, a valve controlling said communication; suction actuated means for moving said valve to open position and a 5 valve device controlling the atmospheric and suction connections of the upper chamber, together with a float in said upper chamber for operating said valve device at substantially the limits of its upper and lower 10 movement, said valve device being arranged

to shift the suction from the upper chamber to the suction actuated means for opening communication with the lower chamber.

7. In the combination defined in claim 6, 15 said valve device being also adapted to simultaneously open the atmospheric connection to the upper chamber when cutting off the suction therefrom.

VOLNEY A. SEARLES.
